UNITED STATES PATENT OFFICE

HAROLD MACHINIST, OF SAN QUENTIN, CALIFORNIA, ASSIGNOR OF ONE-TENTH TO
MARGARET SLATER, OF BERKELEY, CALIFORNIA

LOCK

Application filed September 21, 1931. Serial No. 564,165.

This invention relates to improvements in locks.

The principal object of this invention is to provide a cylindrical lock having a dial arrangement whereby the combination must be actuated first before the key may be inserted within the lock.

A further object is to produce a lock where-in the key-way is so arranged that a person cannot insert a key any appreciable distance into the lock, until the proper combination has been worked out.

A further object is to provide a lock where-in it will be impossible to pick the lock with wires and the like.

A further object is to provide a lock where-in a simple word spells the combination, rather than an intricate numerical combination.

A further object is to produce a lock where-in the combination may be easily changed without the necessity of changing the key.

Other objects and advantages will be apparent during the course of the following description.

In the accompanying drawings forming a part of this specification and in which like numerals are employed to designate like parts throughout the same,

Figure 1 is a side elevation of a lock having my invention applied thereto, as the same would appear when installed upon a door,

Figure 2 is an edge elevation of Fig. 1,

Figures 3, 4 and 5 are diagrammatic views indicating the direction in which the dial is rotated in order to spell out a three letter word combination,

Figures 6 to 16, are detail views of the various parts of my lock,

Figure 17 is a top plan view on an enlarged scale of the lock cylinder,

Figure 18 is a perspective view of the selector dog latch,

Figure 19 is a fragmentary detail view showing a portion of one of the stop rings and its selector ring,

Figures 20, 21 and 22 are diagrammatic views showing the various movements necessary to accomplish an unlocking operation,

Figure 23 is an enlarged detail cross-sec-

tional view taken on the line 23—23 of Fig. 1,

Figure 24 is a diagrammatic view showing in full lines the manner in which the selector dog latch enters the selector notch, and in dotted lines, the manner in which the dog enters one of the depressions for locking rotation of the dial,

Figures 25 and 26 are fragmentary detail cross-sectional views taken on the lines 25—25 and 26—26 respectively, of Fig. 24.

While it is generally conceded that the ordinary cylindrical lock resists to a marked degree the picking thereof, thru the tumbler arrangement, it is admitted however, that experts may readily pick this type of lock.

Applicant has devised means whereby the advantages of the cylindrical lock have been kept, and has added thereto a simple means which surrounds the cylinder, and only, after being arranged in a pre-determined manner, may the mechanism of the cylinder be operated, and thru this arrangement, it would be impossible for a person to insert a key into the key-way, and if a person should attempt to force a key thru the key-way, it would be stopped upon its engagement with the first tumbler, and moreover, this action will also prevent the turning of the dial to effect the combination. This locking of the dial, so to speak, prevents a person from picking the lock or determining the combination thru the "feel method."

In the accompanying drawings wherein for the purpose of illustration is shown a preferred embodiment of my invention, the numeral 5 designates the cylinder of an ordinary Yale type lock, within which is positioned the customary key cylinder 6, having a key-way 7. The customary tumblers and their operating parts are designated as a whole by the numerals 8, 9, 11, 12 and 13. The tumblers 8, 11 and 13 are each provided with pins 14, 16 and 17 respectively, which pins, when in depressed position, have their upper extremities flush with the outer surface of the cylinder 5, it being understood, that all of the tumblers are normally held in locking position by the usual springs. The construction thus far described, would operate as an ordinary lock by simply employ-

ing the ordinary key, the only difference being that I have provided the pins 14, 16 and 17.

In order to prevent a lock of the type thus far described from being picked, I mount upon the cylinder, first a dial member 18. This dial member 18 has a lug 19 extending inwardly and adapted to engage in a selected notch 21 formed in the selector ring 22. This selector ring rides upon the surface of the cylinder 5, and by viewing Figs. 7, and Fig. 23, it will be noted, that this selector ring has an opening 23 therethru, which opening is so arranged, that when this selector ring is rotated to a given point, this opening 23 will be directly above the pin 17. It is here to be noted, that the selector dog latch 24 has a portion thereof extending under the selector ring 22. This dog 24 is adapted to ride in a slot 26 carried in the cylinder 5, (see Figs. 6 and 17). A spacer ring 27 is now placed upon the cylinder, and by viewing Fig. 8, it will be noted that this spacer ring is provided with a slot 28 formed upon its inner periphery, and with lugs 29 also formed upon its inner periphery. These lugs are adapted to travel in key-ways 31 formed in the side of the cylinder, and to thus prevent rotation of the spacer ring. The slot 28 is adapted to overlie the dog 24. It is also to be here noted, that the dial 19 carries a striker pin 32 which extends from the rear of the dial, and overlies the spacer extending beyond the margin thereof, for the purpose of engaging a similar striker pin, to be later described. I now place upon the cylinder a second selector ring 33, (see Fig. 9), which selector ring is provided with notches upon its outer periphery, similar to the notches in the ring 22. This selector ring 33 differs from the selector ring 32 however, in that it has formed upon one face thereof, a deep notch 34, (see Fig. 24) and a plurality of relatively shallow depressions 36. This ring also has an opening 37 therethru, which opening is in alignment with the notches 34, and is adapted to overlie the pin 16, (see Fig. 23). The stop ring 38 is now placed upon the selector ring, and it will here be noted, by viewing Fig. 10, that this stop ring has an inwardly extending lug 39 which enters one of the recesses formed in the outer periphery of the ring 33. This ring 38 carries a stop 41, the purpose of which will be later seen. Also mounted upon the selector ring is a throw-off ring 42, which throw-off ring has an inwardly extending lug 43 which is also adapted to engage one of the notches in the selector ring 33, and it will here be noted, that this throw-off ring is provided with a striker pin 43, which extends on opposite sides of the ring so that one end thereof will engage the striker pin 32, and the opposite end will engage a striker pin to be later described. A spacer ring 44 is now placed up-

on the cylinder, and it will be noted, by viewing Fig. 12, that this spacer ring is provided with lugs 46, to engage the key-way 31 formed in the side of the cylinder. I next place upon the cylinder, the selector ring 47, (see Fig. 13). This selector ring is similar in construction to the selector ring 22, and has an opening 48 which is adapted to be moved into alignment with the pin 14. Mounted upon this ring 47 is a stop ring 49 which is similar in construction to the stop ring 38, and carries a stop lug 50. This ring needs no further discussion. A throw-off ring 51 is now mounted upon the selector ring 47, and corresponds to the throw-off ring 42, the only difference being that in this instance, the striker pin 52 extends only to one side of the ring. A cylindrical casing 53 attaches to the back plate 54, which serves to house the entire mechanism. When the lock is thus assembled as shown in Fig. 23, and assuming that the combination spells the word SKY, the dial 18 is first rotated toward the right, as shown in Fig. 3, until the & sign shows the mark on the upper portion of the cylinder, as shown in Fig. 1. The rotation is continued until the letter S reaches the mark, (see Fig. 3). This rotation causes the various striker pins 32, 43, stop 50, to line up as designated in Fig. 20, first at the & or neutral position, and to rotate further to the S-position. This position is such that the selector ring 47 will now be in such a position, that the opening 48 will overlie the pin 14. By now moving the dial in a reverse direction, as shown in Fig. 4, to the letter K, it will be noted from Fig. 21, that the striker pin 32 has moved out of engagement with the striker pin 43, and into engagement with the stop 41. As the stop 41 and the striker pin 43 move in unison, due to the fact that the rings 38 and 42 are both carried upon the selector ring 33, it will be noted that the stop 50 and striker pin 52, which remained in the dotted S position of Fig. 20, while the striker pin 43 has moved from the dotted position the same distance, that the stop 41 has moved from its dotted position. This travel has caused the selector ring 33 to now be in such a position upon the cylinder that the opening 37 will overlie the pin 16, and also the notches 34 in the edge of the selector ring will be in alignment with the dog 24. By now moving the dial in the direction shown in Fig. 5, to Y, the striker pin 32 will move from the position shown in Fig. 21, to the position shown in Fig. 22. This will cause the selector ring 21 to rotate to a position wherein the opening 23 will overlie the pin 17. By now inserting the key in the key-way, it will be possible for the tumbler 13 to move upwardly, causing the pin 17 to push upon the cam end of the dog 24, thus moving it into its slot 34, and clearing the end of the dog from between the pin and the opening 130

23, thus permitting this pin 17 to rise, and permitting the key to then enter, so as to actuate the other tumblers. The arrangement of the parts is such that should the operator of the lock turn the dial a slight distance beyond the selected letter, this movement would be transmitted to one of the selector rings so as to throw it out of combination. This is very apparent, by viewing Fig. 22. Should the operator, in turning from K back to Y, pass the Y only a slight distance, the pin 32 would engage the pin 43, and would move the selector ring to which it is connected, which in this case represents the letter K, out of alignment, so that the pin 16 could not rise, after the key had been inserted.

Reviewing Figs. 24, 25 and 26, attention is directed to the fact that in some types of locks, it is possible to pick the lock by feeling. Applicant has therefore provided on the surface of the selector ring 33, a series of notches, merely for the purpose of deceiving the person trying to pick the lock. As this ring is rotated thru the striker pin 32, which is attached to the dial 18, it will be apparent that if this ring can be held in some manner, that the dial cannot be rotated. Therefore, I have caused a locking effect as soon as the person attempts to place a key or other instrument in the key-slot. In Fig. 24, I have shown on the left hand side of the figure the manner in which the dog 24 enters the selector ring slot 34 when the selector ring is in proper position, that is; when all of the combinations have been completed. This is shown in side elevation in Fig. 25. Should a person attempt to place the key in the key-way before the combination has been completed, the result will be, that the placing of the key will tend to move the tumbler upwardly, with a result that the pin 17 will engage the dog and move it against the face of the selector ring 33, and assuming that the dial is turned, the dog will enter one of the notches 36, and arrest further movement of the selector.

It will thus be apparent, that with my lock, it would be impossible to insert a key or other instrument in the lock for the purpose of picking it, and that if it is attempted to be forced, that the combination mechanism will immediately be locked, so that the various letters of the combination cannot be selected. It is also apparent that the lock cannot be operated until all three of the letters have been brought into exact registry, so that the pins of the tumblers may pass upwardly thru the selector rings, and further apparent, that should a person turn the dial slightly beyond the pre-determined letter, that the combination will be destroyed, and the lock cannot be operated.

It is to be understood that the drawings of Figs. 20, 21 and 22 are greatly exaggerated.

ated, and therefore, the amount of movement of relative parts, is comparatively small to that shown. With this lock, it is possible to change the combination as often as is desired without the necessity of securing new keys, which is of considerable advantage, particularly in banks or like institutions, where it is the practice to change the locks and combinations at definite periods.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a lock, the combination with a lock cylinder and the barrel of a key actuated mechanism positioned therein, said mechanism including a plurality of pins adapted to be projected beyond the surface of said barrel, a plurality of selector rings rotatably mounted on said barrel, a dial mounted on said barrel, means carried by said dial and said selector rings whereby said selector rings may be rotated, each of said selector rings having an opening formed therein, and adapted to receive the ends of said pins.

2. In a device of the character described, the combination with a cylinder lock comprising a barrel having a key actuated mechanism positioned therein, said mechanism including a plurality of pins adapted to be projected from said barrel, a plurality of selector rings rotatably positioned on said barrel, each of said selector rings having an opening formed therethru, a stop ring mounted on each selector ring, a throw-off ring mounted on certain of said selector rings, a dial carried by one of said selector rings, a striker pin carried by said dial and adapted to actuate said selector rings whereby said rings are free to rotate relative to said barrel.

3. In a device of the character described, the combination with a lock cylinder embodying a tumbler barrel, a key actuated mechanism positioned therein, said mechanism including a plurality of pins adapted to be projected from said tumbler barrel, a plurality of selector rings rotatably mounted on said tumbler barrel, one of said selector rings having notches formed on one of its faces and a dog slidably mounted in said barrel and adapted to be moved into contact with said notches in said selector ring, said dog being actuated thru the movement of one of said key actuated pins, each of said selector rings having an opening formed therethru, a stop ring mounted on certain of said selector rings, a throw-off ring mounted on certain of said selector rings, dial mounted on one of said selector rings, a striker pin carried by said

dial and adapted to engage striker pins mounted on certain of said rings whereby said rings may be rotated relative to said barrel.

4. In a device of the character described, the combination with a cylinder lock having a tumbler barrel, of a plurality of selector rings positioned on said tumbler barrel and adapted to rotate thereabout, dial means for rotating said selectors to effect the combination, and means associated with one of said selectors to prevent the actuation of the remaining selectors of the lock.

5. In combination, a cylinder lock having a tumbler barrel, a plurality of tumbler pins adapted to be projected from said barrel, a plurality of selector rings positioned on said barrel, each of said selectors having an opening therein adapted to receive said pins, and dial means associated with said tumbler barrel for rotating said selectors successively, whereby said selector openings are moved into alignment with said pins to permit the actuation of said pins to release the lock.

6. In a device of the character described, the combination with a lock cylinder comprising a tumbler barrel having a key actuated mechanism positioned therein, said mechanism including a plurality of tumbler pins adapted to be projected from said barrel, a plurality of selector rings rotatably mounted on said barrel, each of said selector rings having an opening formed therethru, a stop ring mounted on certain of said selector rings, a throw-off ring mounted on certain of said selector rings, a dial associated with one of said selector rings, a striker pin carried by said dial and adapted to engage striker pins mounted on certain of said selector rings whereby said rings are rendered free to rotate relative to said barrel, and latch means co-acting with one of said selectors to prevent the actuation of the first tumbler until a proper combination has been effected.

In testimony whereof I affix my signature.
HAROLD MACHINIST.
